BY

UNITED STATES PATENT OFFICE

WILLIAM M. SCOTT, OF TREDYFFRIN TOWNSHIP, CHESTER COUNTY, PENNSYLVANIA,
ASSIGNOR TO I-T-E CIRCUIT BREAKER COMPANY, OF PHILADELPHIA, PENNSYLVANIA, A CORPORATION OF NEW JERSEY

ELECTRICAL SWITCHING APPARATUS

Application filed April 12, 1929. Serial No. 354,480.

My invention relates to electrical switching apparatus and more particularly to automatic switching apparatus of the electromagnetic type.

5 My invention resides in switch operating structure for a circuit breaker, particularly of the non-closable type, wherein the movable contact structure of the circuit breaker is caught and held in its fully open position to preclude rebounding, by a holding latch which is released to permit movement of the contact structure to closed position upon movement of the switch operating structure.

10 15 My invention further resides in a system of dual protection for a circuit wherein an automatic circuit breaker connected in said circuit is tripped open in response to either a predetermined instantaneous value of 20 overload or a predetermined and continued overload of lower magnitude; and more particularly said tripping means comprises two independently actuated armatures selectively coacting with a common latch actuator of the circuit breaker, one of said armatures have relatively small mass and actuated upon occurrence of a predetermined instantaneous value of overload, and the other armature having relatively greater mass and 25 operatively connected to a start-delay or sucker element, whereby actuation thereof to trip open the circuit breaker is effected only upon occurrence of predetermined and prolonged overload.

30 35 My invention further resides in means for effecting a common adjustment of a pair of armatures, a separate adjustment of one armature affecting the tripping point of another, whereby simultaneous adjustment of 40 said armatures varies the tripping range of one of them within predetermined limits while maintaining the tripping point of the other substantially constant; and more particularly the pivotal mountings for said armatures are disposed transversely of, or at an appreciable angle to, another portion of the magnetic circuit whereby the magnetic impulses, as in an alternating current system, acting upon an armature at its mounting, 45 do not directly oppose the force of gravity,

thereby substantially obviating chattering or vibration of said armature.

50 My invention further resides in a combination of a switch or automatic circuit breaker and structure movable to either one of a plurality of positions, in one of which it permits free or normal operation of the switch or circuit breaker, and in another of which it prevents actuation or operation of the switch or circuit breaker; and more particularly prevents reclosure of the switch or circuit breaker; and more particularly there is provided means for latching or holding a switch or circuit breaker housing to its supporting structure or base, and so 55 related to the aforesaid combination that a single locking means, such as a padlock or equivalent, may simultaneously lock it and the aforesaid movable structure, the latter in either of its positions aforesaid.

60 65 My invention further resides in apparatus of the character hereinafter described and claimed.

70 For an understanding of my invention, reference is had to the accompanying drawings, in which:—

75 Fig. 1 is a side elevational view of electrical switching apparatus.

Fig. 1a is a side view of core structure.

Fig. 1b is a front view of the structure 80 illustrated in Fig. 1a, with coacting armatures.

Fig. 23 is a lower plan view of Fig. 21.

Fig. 24 is a view showing the parts in Fig. 22 in another position.

Referring to Figs. 1 and 2, a base or panel 1 of suitable insulating material, is provided with barriers 1a extending transversely thereto and has mounted thereon electrical switching apparatus comprising a stationary contact 2 suitably secured to the base, as by a conducting stud 3 which comprises a lead conductor of the circuit to be protected, and a movable contact 4 mounted upon a transversely extending bar or support 5, and electrically connected by a flexible conducting strip 6 to a terminal 7 on the bracket 8 secured to base 1. Terminal 7 is connected to one end of an overload coil 9 whose other end is connected to the conducting stud 10 comprising the other lead from the circuit to be protected.

Cooperating with movable contact 4, and mounted also upon the switch arm support 5 is an auxiliary or arcing contact 11 carried on the end of a resilient conducting arm 12. In the closed position of the switch, contact 11 is in engagement with a contact 13 suitably secured to the base, as by screw 13a, which is positioned and spaced with respect to contact 2 by a raised portion or boss 13b forming a part of the base. Means for extinguishing the arc between contacts 11 and 13, referring more particularly to Figs. 8 and 9, comprises a pair of blow-out coils 14 and 15 arranged on each side of the contacts in the usual manner, and having their inner ends connected to each other by a conducting strip or bridge 16, and their outer ends connected together by a conducting strip 17 having a rectangular opening 18 therein for a purpose hereinafter described.

Conducting strip 16 is suitably secured to the base by contact 13 and is in electrical contact therewith. The conducting strip 17 is likewise clamped to the base by contact 2, the extension of which passes through aperture 18, thereby connecting coils 14 and 15 in parallel between contacts 2 and 13.

Insulating enclosing structure for the blow-out coils, referring more particularly to Figs. 3 to 7 inclusive, comprises parti-

tions or walls 19 preferably integrally mounted to the base or panel 1 as by moulding, and of substantially the same material, and cover members 20 of arc-resisting material detachably secured with respect to the base and partitions. As viewed in Figs. 6 and 7, an individual pair of blow-out coils are disposed adjacent the opposing faces of two partitions or walls, and are suitably housed by the cup-like covers 20 which form with partitions 19 receptacles for completely enclosing the blow-out coils. Except for the end walls, the members 19 form common wall structure for a pair of unrelated coils. Each partition or wall 19, as previously mentioned, is preferably moulded to base 1, forming an integral part therewith, and is of insulating material. The cover members are so designed that they are readily removable to afford access to the coils. To this end, the cover members 20 are each provided with offset portions 21, Figs. 4 and 5, adapted to abut each other when the covers are in position to shield and protect an appropriate portion of base 1 not shielded by the contact 13, and to furthermore space the cover members from each other to provide suitable clearance for the movable contact element between the same. The interior of each cover member 20 is provided with a shoulder 22 extending along three sides of the same for engaging the corresponding edges of a partition 19 to relatively position the same. The edges of the cover abutting base 1 seat within a correspondingly shaped depression 20a in the base 1 and have a pair of notches 23 and 24 therein for receiving the bridging conductors 16 and 17 respectively of the blow-out coils. The front side of the cover partially overlying the outer edge of the partition is provided with a semi-circular notch 25 and a longitudinally extending recess 26 for receiving a holding screw 27 and a clamp 28. Screw 27 is secured, as by an insert 27a, to the front edge of partition 19 and serves to clamp the front edge of cover 20 to the partition. As viewed in Fig. 6, two of the partitions 19, when three pairs of blow-out coils are employed, have a cover member mounted on each side thereof and clamped thereto by common clamping structure 27 and 28. Accordingly, quick and easy access to the blow-out coils may be accomplished by simply unloosening screw 27 and clamp 28. The features of construction relating to the blow-out coils and associated elements are claimed in my co-pending divisional application Serial No. 441,759, filed April 5, 1930.

The movable switch structure, comprising the main contact 4 and the arcing contact 11 is carried by a transverse supporting bar 5 suitably secured to a flange 29a of a member 29 pivotally mounted at 30 to a frame 31 on the base 1. Referring more particularly to Figs. 10 and 11, the switch operating

structure comprises a pair of toggle links 32 and 33 pivotally connected to each other at 34 and having their opposite ends pivotally connected at 35 and 36 to members 29 and 37 respectively. Member 37 is pivotally mounted at 38 to the fixed support or bracket 31 and carries at its outer end a latch 39 pivoted at 40, having a notched portion 41 for engaging the extension or lock 70
10 ing detent 42 of the toggle link 33. A latch member 43 pivotally carried by member 29 at 35 comprises a notched portion or recess 44 at the lower edge of its free end, and a shoulder 45 abutting flange 29a of member 29 to 75
15 prevent further rotation in a clockwise direction. As viewed in Fig. 10, the switch operating structure is in circuit-closing position, and latch 43 is maintained out of engagement with the other elements of the 80
20 structure by shoulder 45. Toggle 32-33 is shown in extended position although slightly undertravelled, and is maintained in such position by latch 39 carried by the main operating lever 37, which forms with link 32
25 a second toggle comprising pivots 35, 34 and 38. Link 33 and arm 37 being latched to each other, the two members operate as a unit to form the second toggle which is over-travelled to a small extent, pivot 34
30 being slightly above the center line of pivots 35 and 38, and therefore remains in this position until tripped in a manner hereinafter described. Latch 39 comprises a tail-like extension 39a adapted to be engaged by a 85
35 tripping bar 46 to rotate the latch in a clockwise direction. Upon tripping movement of member 46 to move latch 39 clockwise, the shoulder 41 of latch 39 moves out of engagement with detent 42 of the toggle 90
40 link 33, releasing link 33 from the operating arm 37 and permitting the undertravelled toggle 32-33 to collapse, thereby causing immediate collapse of the operating structure to the position shown in Fig. 11, 95
45 which is representative of the open position of the switch. Member 29 is biased by a spring 47 in a clockwise direction, one end of the spring being secured to an extension 48 of member 29 and the other end to a lug 50 49 mounted upon the operating arm 37 (Figs. 1 and 2). As the toggle operating structure moves to the open circuit position illustrated in Fig. 11 under the influence of gravity and spring 47, latch 43 will move 100
55 with member 29 in a clockwise direction and will engage by its camming edge 43a pivot pin 36 interconnecting the link 33 and the operating arm 37. Accordingly, latch 43 will ride upon pivot pin 36 until notch 44
60 permits the latch to drop into engagement with the same to lock member 29 in the position shown in Fig. 11. Counterclockwise rebound of member 29 is accordingly checked 105
65 while latch 43 is in engagement with pin 36, due to the fact that the operating member 110
70 75 80 85 90 95 100 105 110 115 120 125 130

37, by which pivot pin 36 is carried, is mounted on the stationary bracket 31. Release of latch 43 from the pivot pin 36 is accomplished during the usual procedure in actuating the switch to closed position as follows: Operating arm 37 is first rotated in a counter-clockwise direction in order that latch 39 may engage detent 42 of the toggle link 33 to latch the two members together. As arm 37 is so rotated, the pivot pin 36 carried thereby also moves in a counter-clockwise and downward direction, and since movement of latch 43 in a clockwise direction is limited by the stop means previously referred to, pin 36 will move out of notch 44. Accordingly, after link 33 and arm 37 have been latched together the operating arm 37 is moved in clockwise direction to extend the toggle structure to circuit-closing position as illustrated in Fig. 10.

It will be noted that member 29, on which the movable contacts of the switch are mounted as a unit, is caught and held in substantially its fully opened circuit position by latch 43, which prevents the movable contact structure from rebounding towards the stationary contacts, and from vibrating violently as in the case where the switching mechanism is caused to open with more than the usual force. Rebounding of the movable contacts any substantial part of their total movement is objectionable in practice, and if the rebound should cause the movable contacts to touch their cooperating stationary contacts, freezing of the same together would in all probability result.

The supporting bar 5 for the movable contacts, referring to Figs. 12, 13, and 14, comprises an insulating bar having recesses 50 in one side thereof for receiving conducting strips 6 and the contact supporting strips 4 and 12. Inserts 51 extend through member 5 for receiving securing means, as screws, to hold the contact members in position. V-shaped notches 52 are also provided for permitting clearance of springs 47 when member 5 is moved clockwise during opening of the switch. Lugs 53 extend below the lower surface of member 5, and comprise a sloping face 53a for supporting the flexible strip 6 and preventing it from contacting with terminal stud 10. A boss or lug 54 extending from the front face of member 5 comprises a recess 55 within which is mounted an arm 56 carrying an indicating device 57, whose position indicates the circuit position of the circuit breaker.

Electromagnetic means for automatically tripping the circuit breaker comprise an electromagnet having a coil 9, a hollow core 58 and pole pieces 59 and 60 at opposite ends of the core. The front pole piece 60 is clamped, together with a transversely extending coil support or bar 61, hereinafter described, in position by suitable

means as a bolt 62 extending through core 58 and clamped to base 1. Core 58, referring to Figs. 1a and 1b, comprises a hollow tubular member to which are secured pole piece 59 at one end and pole piece 60 at the other end. Pole piece 60 and core 58 are slotted, or divided, as at 58a, so that the magnetic field from the lower tip of pole piece 60 will vary according to the proportion in which the pole piece is divided. Slot 58a, though preferably extending partly back through the core, may extend back any desired distance up to the entire length of the core. As will be noted in Fig. 1b, slot 58a divides the lower outwardly turned portion of the pole piece 60 into parts 60a and 60b, part 60a having appreciably less cross section than part 60b. Accordingly, for a given amount of flux produced by the overload coil 9, and neglecting saturation effects, the strength of the magnetic fields passing through the divided portions of pole piece 60 varies approximately as their respective cross sections. In Fig. 1b the relative positions of armatures 63 and 64 with respect to each other and the pole piece, are somewhat exaggerated and do not necessarily represent the actual positioning of said elements in practice.

Member 61, Figs. 19 and 20, has recesses 83 for receiving the front pole pieces of the individual trip magnets, and notches 84 within which the edges of barriers 1a are fitted. Apertures 85 for receiving the latch actuating pins 81 for engaging tripping bar 46 extend vertically through bar 61 and comprise three individual pairs corresponding to the three pairs of armatures herein-after described. The apertures 86 receive bolts 62 for clamping the bar in position. The lower edge of bar 61 seats upon offset portions of barriers 1a, Fig. 1.

A pair of armatures 63 and 64 are pivoted independently of each other upon a supporting pin 65 carried by lugs 66 forming a part of bracket 31 and of non-magnetic material, such as brass for example. Lugs 66 extend transversely of or at an appreciable angle to the lower portion of pole piece 59 for a purpose hereinafter described. Armature 63, Figs. 15 and 16, comprises a portion 67 of magnetic material having a downwardly turned lug 68 at its pivoted end. The armature is suitably weighted by a member 69 of non-magnetic material, such as brass for example, the non-magnetic member being turned upwardly at its outer end to provide greater mass for a given over-all length of the armature. An aperture 70 for receiving a pivot pin 71 provides means for connecting armature 63 to a sucker apparatus S comprising a time-delay feature. The pivotal bearing of armature 63 comprises a strip

of non-magnetic material 72 secured to the under side of the armature and having a bent-over portion 73 and a struck-out portion or tongue 74 within which pivot pin 65 is disposed. Member 72 also comprises transversely extending portions 75 for properly spacing armature 63 with respect to the other armature 64. Armature 64 is similar in construction to armature 63 and comprises a magnetizable portion 76 to the under side of which is fastened a non-magnetic weight 77 such as brass. The pivotal mounting for this armature comprises a member 78 having bearing portions 79 and 80 formed in the manner above described. Armatures 63 and 64 are each mounted transversely along pivot 65, armature 63 being connected to the time-delay apparatus S, and armature 64 being free to move independently of armature 63, as in response to an instantaneous impulse of sufficient magnitude. Armature 64 has appreciably less magnetic susceptibility than armature 63, its iron or magnetizable member 76 being considerably smaller than the corresponding member 67 of armature 63, and in its inactive position in the circuit breaker, armature 64 is more remote from pole piece 60 than is armature 63. By suitable variations of these factors and of the total weights of the respective armatures, any desired relation may be secured between their respective tripping points.

By magnetic susceptibility is meant the responsiveness to magnetic attraction, and in the present instance it is dependent upon a number of factors. These factors include the cross section of the magnetizable portion of an armature as compared with the total weight of the moving system; the relative areas of the armatures exposed to the pole of the magnet; the respective distance of each armature from the pole of the magnet in its normally unattracted position; and the relation of the distance of one armature to that of the other with respect to the pole of the magnet.

Referring to Figs. 1 and 2, the armatures 63 and 64 are disposed in their unattracted positions at varying distances from pole piece 60 and in coacting relation with the divided pole portions so that the field of the pole portion 60a acts upon armature 64, and the field of portion 60b acts upon larger armature 63. Accordingly, the armatures 63 and 64 are individually acted upon by magnetic fields whose strength in general depends upon the ratio in which the pole piece 60 is divided.

Each of the armatures is adapted to engage and push upwardly a corresponding latch-actuating pin 81 whose upper portion 82 may freely engage the latch-tripping bar 46. Accordingly, when either armature 63 or 64 is urged by the field of coil 9 in a

counterclockwise direction towards pole piece 60 to engage its corresponding tripping pin 81, bar 46 will be lifted to trip latch 39 and permit opening of the switch.

5 It should be noted at this point that the magnetizable portions of armatures 63 and 64 are disposed substantially transversely of or at a substantial angle to the lower extending portion of pole piece 59, and accordingly are acted upon by magnetic forces tending to move the armatures horizontally or nearly so towards the said pole extension. In previous practice, it has been customary to mount the armatures below the extension 15 of the pole piece, and to utilize a spring or equivalent to prevent chattering or vibration of the armature when used in an alternating current system. This chattering is due to the fact that the magnetic forces tending to 20 attract the armature upwardly act in direct opposition to the force of gravity, which is constant. Accordingly, when the magnetic force fluctuates or pulsates, chattering of the armature will result when this construction is used unless special means are 25 used to prevent it. In the construction shown in Fig. 1, the magnetic forces at the pivot ends of the armatures act to move them horizontally, and not vertically, and so act 30 substantially at right angles to the force of gravity. Accordingly, the pulsating force tending to produce chattering of the armature is either materially minimized or reduced to zero without the use of additional 35 means to this end. There is no appreciable chattering at the free ends of the armatures due to the weight of the armatures and their spacing from the pole piece 60. The armatures do not pull up until current flowing in the coil 9 reaches the operating values 40 for which the armatures are respectively adjusted, at which time one of the armatures, depending upon the particular condition existing, will pull up (after a suitable time 45 delay in the case of armature 67) and trip the circuit breaker.

The armatures 63 and 64 are so proportioned and placed with respect to the pole piece 60 that armature 63 will react to a 50 much smaller current than will armature 64; due, however, to the action of the time limit feature associated with the armature 63 its response to such current requires that it be sustained for an appreciable period of time. 55 In the case of unduly heavy current flow, armature 64 responds instantly to open the circuit breaker. Accordingly there is provided a dual system of protection wherein the circuit to be protected is opened instantaneously upon occurrence of a very heavy overload or upon the occurrence of a more moderate overload unduly long sustained, since relatively small transient overloads are not sufficiently dangerous to apparatus such 60 as motors to warrant the opening of the cir-

cuit and consequent interruption of service.

Referring to Figs 21 to 24 inclusive, there is shown means for housing switching apparatus and for concurrently locking the housing and switching apparatus in predetermined relations. The base or panel member 1 has mounted on the rear side thereof a housing 90, within which are disposed the terminal connections (not shown) for the switching apparatus and the usual leads 70 emerging by way of conduit 91. A cover or switch housing structure 92 is pivotally mounted at 93 upon the rear housing 90, and is pivotally movable with respect to base 1, which also is pivotally movable with respect to housing 90. Upon the front face 94 of housing 92 is mounted an operating handle 95 which extends through the front wall of the housing within bearing 95a 80 and terminates in a switch-actuating member 96, comprising jaw-like portions 97 and 98 (Fig. 22). An aperture 57a in wall 94 permits inspection of indicator 57. The operating handle 95 is normally biased to the position shown in Fig. 22 by a spring 99 90 having one end connected to a lug 100 on the member 96, and the other end to an anchored member 101 secured to the bottom wall of housing 92. A locking arm 102 pivoted to wall 94 at 103 comprises an extension 104 terminating in a recessed portion 105, and comprising at its opposite end an enlarged portion 106 provided with apertures 107 and 108 for a purpose hereinafter described. Arm 102 is normally biased by a 100 spring 109, also secured to anchored member 101, to the position shown in Fig. 22.

Referring to Fig. 23, the lower side of housing 92 is provided with a latch 110 pivotally mounted to the housing at 111 and comprising a transversely extending flange 112 for facilitating operation thereof. One end of latch 110 is provided with a notched recess 113 adapted to receive a pin or lug 114 carried by the overlying portion of a lug 115 which is secured to housing 90. Accordingly, when the parts are in the position shown in Fig. 23, housing 92 is rigidly secured with respect to housing 90. The opposite end of latch 110 is provided with a downwardly turned portion 116 provided with an aperture 117, and adapted to register when in the position shown in Fig. 23 with an aperture 118 in a lug 119 secured to the lower wall of housing 92. Accordingly when lever 102 is moved so that either aperture 107 or 108 registers with apertures 117 and 118, a padlock or equivalent locking device may be inserted in the apertures to relatively lock latch 110, cover 92 and lever 102. 115 120 125

The oppositely disposed jaw portions 97 and 98 of the operating member 96 are in the path of movement of the outer portion of the main switch-operating arm 37 hav- 130

ing a roller 37a pivotally mounted at 37b to arm 37.

The operation of the apparatus is as follows:—

- 5 Assuming the switching apparatus to be in the open position, and the switch locking members to be in the position shown in Fig. 22, handle 95 is first rotated in clockwise direction, whereupon jaw portion 98 engages 10 roller 37a to lift the same and to rotate the operating arm 37 in a counterclockwise direction. Such movement of the operating arm effects release of latch 43 tending to restrain the contacts in open position, and 15 upon further movement causes latch 39 to engage detent 42 of the undertravelled toggle structure in the manner previously described. Handle 95 is accordingly rotated in the opposite or counterclockwise direction, 20 whereupon jaw portion 97 engages roller 37a to rotate the operating arm 37 in a clockwise direction to extend the toggle structure to circuit-closing position. Upon completion 25 of the circuit-closing movement, the handle is released and assumes the position shown in Fig. 22 due to the influence of spring 99. It will be noted that during the above described operation, lever 102 in its 30 normally biased position does not interfere with the movement of the actuating member 96, and accordingly lever 102, together with latch 110, may be locked with respect to the stationary lug 119 by passing a padlock through apertures 118, 108 and 117. When 35 so locked, the switching apparatus is locked within housings 90 and 92, but is free to be moved to open or closed positions. If now it is desired to lock the switching apparatus in its open position, arm 95 is first rotated 40 in a clockwise direction so that pin 96a on member 96 will be free to clear the upper end of extension 104 to register with notch 105. However, such required movement brings the lower jaw portion 98 into contact 45 with roller 37a to trip open the switch, thereby insuring that the switch is in open position before the locking operation is completed. The padlock or equivalent having been removed from apertures 108, etc., the extension 50 106 of lever 102 is pushed into the position shown in Fig. 24, wherein aperture 118 of the locking lug is in registry with aperture 107 of the lever. The members are locked in this position, after which handle 55 95 is released, permitting pin 96a to seat within notch 105 of the locking lever to prevent further movement of member 96 in a counterclockwise direction. Since it is essential that the main operating arm 37 be rotated 60 first in one direction, and then in the other direction to complete closure of the switch, it will be apparent that the switch is locked in open position as long as the members 102 and 96 are in the positions 65 shown in Fig. 24. Upon removal of the

padlock from apertures 107, etc., spring 109 moves lever 102 to cam the pin 96a out of notch 105, whereupon member 96, under the influence of its spring, assumes its normal position.

In the opening movement of the circuit breaker, the main movable contact member 4 is first withdrawn from the fixed contact 2; while for the instant, movable contact 11 maintains its engagement with fixed contact 13, thus bringing the blow-out coils into series with the main circuit and thereby rendering them effective to rupture the arc drawn in the space between them incident upon the further opening of the switch and consequent withdrawal of contact 11 from engagement with contact 13.

In order to prevent arcing at the main contacts of the circuit breaker, it is essential that the impedance of the blow-out coils shall be a minimum consistent with the desired magnetic effect. High blow-out efficiency is attained by disposing the two coils on opposite sides of the arcing chamber, the effectiveness thus secured being such that iron may be altogether omitted from the magnetic circuit and coils of relatively few turns are found to suffice. The cover members 20 which shield the blow-out coils, the partition members 19, and the base area 95 above the contact 13, are of material having high arc-resisting characteristics; accordingly, base 1 and partitions 19, being effectively shielded from arcing, the material from which these are moulded may be selected with reference to its insulating qualities rather than for its ability to resist arcing.

With the circuit breaker in the closed position, armatures 63 and 64, upon the occurrence of predetermined overload conditions in the circuit to be protected, selectively actuate the latch trip bar 46 to cause the circuit breaker to open. For example: If an overload of 200 amperes or more is deemed excessive even though occurring only for an instant, armature 64 may be so adjusted that it will immediately open the circuit breaker when this or heavier overload occurs. Armature 63, however, is not actuated by this high instantaneous current since the suckers of the time limit device does not release its hold immediately but only in response to a prolonged force. Accordingly, in the event of purely transient overloads of less than 200 amperes, neither armature 63 nor 64 will respond to trip the circuit breaker. In general, the desired instantaneous trip out current of a given circuit breaker is fixed at about eight times the rated capacity of the circuit breaker, while on the other hand, the point of "trip-out" on sustained smaller current must be subject to a considerable range of adjustment. This adjustment is obtained by movement 130

of armature 63 toward or away from pole piece 60, this movement being effected by corresponding movement of the time limit containing case S along the stirrup 130 to which it may be secured in the desired position by means of the screw 131, the corresponding tripping points being indicated by a suitable calibration scale on the front face of the stirrup 130. The position of armature 63 with respect to armature 64 affects also the tripping point of armature 64, i. e., the magnitude of current which will cause tripping movement of armature 64; means must be provided therefore such that for any setting of armature 63, armature 64 will be so positioned that its tripping point will remain constant. This effect is secured by having armature 64 rest upon a point 132 of the time limit case considerably more remote from the pivot 65 than is the point 71 which supports the armature 63 with respect to this case. By a proper determination of the relative distances of the respective points of support 71 and 132 from the pivot pin 65, the tripping point of armature 64 is maintained practically constant throughout the entire range of adjustment of itself and armature 63.

Upon the positions with respect to each other of armatures 63 and 64, because both are magnetically in parallel in the same magnetic field, depends the relative magnitudes of the fluxes through them; that is to say, each armature effects diversion of flux from the other, and the amount of diversion from armature 63, for example, depends upon the relative position of armature 64. In addition to the fact hereinbefore stated that the position of the armature 63 with respect to armature 64 affects the tripping point of the latter, it is also inherently true that the position of the armature 64 with respect to the armature 63, determines the diversion of flux from the armature 63, and determines the extent of delay effected by the retarding device S. The amount of diversion by one armature upon the other may be affected by their hereinbefore mentioned relative magnetic susceptibilities, sizes, and relative weight, and by their positions with respect to the pole pieces.

What I claim is:

1. The combination with automatic switching apparatus comprising a movable contact member, and a main operating member for said contact member, of means carried by one of said members and catching the other for restraining said movable contact member substantially upon completion of its movement to open position to prevent re-bounding of said movable contact member.

2. The combination with automatic switching apparatus comprising a movable

contact member, and a main operating member for said contact member, of latching means coacting with said contact member and operating member engaging with and restraining said movable contact member substantially upon completion of its movement to open position to prevent re-bounding of said movable contact member, said latching means adapted to be released upon subsequent movement of the operating member to effect closing movement of said contact member. 75

3. The combination with automatic switching apparatus of the non-closable type comprising a movable contact member, a main operating lever, and means detachably connecting said contact member to said lever, of means for catching and restraining said movable contact member in open position comprising a latch member carried by said contact member and adapted to engage a portion of said operating lever as the movable contact member reaches its fully open position. 80

4. The combination with automatic switching apparatus of the non-closable type comprising a movable contact member, a main operating lever, means detachably connecting said contact member to said lever, and tripping means for releasing said detachable connection to permit opening movement of said contact member, of means for catching and restraining said movable contact member in open position comprising a latch member carried by said contact member and adapted to engage a portion of said operating lever as the movable contact member reaches its fully open position, said latching member released from the operating lever upon movement of the same to re-establish operative connection with said movable contact member prior to closing movement of said contact member. 100 90

5. The combination with automatic switching apparatus of the non-closable type comprising a movable contact member, a main operating lever, means detachably connecting said contact member to said lever, and tripping means for releasing said detachable connection to permit opening movement of said contact member, of means engaging with and restraining said movable contact member in open position upon tripping of the switch, said means adapted to be moved out of restraining engagement upon movement of the operating lever to re-establish the connection between the same and said contact member prior to movement of the contact member to closed position. 110 115

6. The combination with automatic switching apparatus of the non-closable type comprising a movable contact member, a main operating lever, an undertrav- 120 125 elled toggle structure connected to said con- 130

- tact member and lever, means detachably connecting an element of said structure to said operating lever to form an overtravelled toggle, and tripping means for breaking said connection to permit collapse of the undertravelled toggle structure and opening of the switch, of means for catching and restraining said movable contact member in open position comprising a latch member carried by said movable contact member adapted to engage a portion of the operating lever at a point removed from its pivot, said contact member being released from said latching engagement upon movement of the operating lever to reestablish connection with said toggle structure.
7. The combination with automatic switching apparatus of the non-closable type comprising a movable contact member, a main operating lever, an undertravelled toggle structure connected to said contact member and said arm at a point removed from its pivot, means detachably connecting an element of said structure to said operating lever to form an overtravelled toggle, and tripping means for breaking said connection to permit collapse of the undertravelled toggle structure and opening of the switch, of means for catching and restraining said movable contact member in open position comprising a latch member carried by that end of the undertravelled toggle connected to the movable contact member and adapted to engage the opposite end of said toggle connected to the operating lever, said contact member being released from said latching engagement upon movement of the operating lever to reestablish connection with said toggle structure.
8. An electromagnet comprising magnetizable core structure, a pivoted armature completing a magnetic circuit with said core structure when in substantially horizontal position, and means mounting said armature to said structure whereby the magnetic forces acting on the pivot of said armature are at substantially right angles to the force of gravity acting thereon and tend to effect movement in a substantially horizontal plane.
9. An electromagnet comprising magnetizable core structure, a pivoted armature completing a magnetic circuit with said structure when in substantially horizontal position, and means mounting said armature to said structure whereby the magnetic forces acting on the pivot of said armature are at a relatively great angle to the force of gravity acting thereon.
10. An electromagnet comprising magnetizable core structure having a depending pole piece, a pivoted armature normally positioned solely by gravity completing a magnetic circuit with said structure when in substantially horizontal position, and means mounting said armature adjacent and substantially laterally of said pole piece to preclude chattering of the armature.
11. An electromagnet comprising magnetizable core structure having a depending pole piece, a pivoted armature completing a magnetic circuit with said structure when in substantially horizontal position, and non-magnetic means upon which said armature is mounted disposed substantially laterally of and at a relatively great angle to the lower extension of said pole piece whereby the magnetic forces tending to attract said armature towards said pole piece act at an appreciable angle to the force of gravity.
12. A magnetic structure comprising a core, pole pieces, an energizing coil therefor, a plurality of armatures coacting selectively therewith, and adjusting means common to said armatures unequally effective thereupon, said adjusting means adapted to affect said selectivity in a predetermined relation upon movement thereof.
13. The combination with an automatic circuit breaker comprising movable contact structure, means for retaining said structure in normal position, and tripping means therefor, of a magnetic structure comprising a core, pole pieces, an energizing coil therefor, a plurality of armatures coacting selectively therewith to actuate said tripping means, and adjusting means common to said armatures unequally effective thereupon, said adjusting means adapted to affect said selectivity in a predetermined relation upon movement thereof.
14. The combination with an automatic circuit breaker comprising movable contact structure, means for retaining said structure in normal position, and tripping means therefor, of magnetic structure comprising an electromagnet, a plurality of armatures coacting selectively therewith to actuate said tripping means, and means common to said armatures for adjusting them simultaneously and differentially with respect to said electromagnet.
15. The combination with an automatic circuit breaker comprising movable contact structure, means for retaining said structure in normal position, and tripping means therefor, of magnetic structure comprising an electromagnet, a plurality of armatures coacting selectively therewith to actuate said tripping means, the magnetic susceptibility of said armatures being affected by their relative positioning with respect to each other and said electromagnet, and means common to said armatures for adjusting them simultaneously and differentially with respect to said electromagnet whereby the magnetic susceptibility of one of said armatures with respect to said electromagnet is maintained substantially constant.

16. An electromagnet comprising a magnetizable core member, a pole piece for said core member divided into components for dividing the magnetic field, and a plurality of armatures operatively related respectively to said pole piece components. 70
17. An electromagnet comprising a divided magnetizable core member, a pole piece divided into components operatively related respectively to the components of said core member for dividing the magnetic field, and a plurality of armatures operatively related respectively to said pole piece components. 75
18. An electromagnet comprising a magnetizable core member, a pole piece coaxing with said core member divided into a plurality of components for dividing the magnetic field, and a plurality of armatures coaxing respectively with the components of said pole piece and disposed at different distances therefrom. 80
19. An electromagnet comprising a magnetizable core member, a pole piece coaxing with said core member and divided into components of different widths for dividing the magnetic field, and a plurality of armatures of different widths coaxing respectively with said pole piece components. 85
20. An electromagnet comprising a magnetizable core member, a pole piece coaxing with said core member and divided into components of different widths for dividing the magnetic field, and a plurality of armatures of different widths coaxing respectively with said pole piece components and disposed at different distances therefrom. 90
21. The combination with a movable contact member, of means for restraining it in normal position, and electromagnetic means for causing actuation of said restraining means under different electrical conditions comprising a magnetizable core member, a pole piece for said core member divided into components for dividing the magnetic field, and a plurality of armatures for actuating said restraining means cooperatively related respectively with said pole piece components. 95
22. The combination with a movable contact member, of means for restraining it in normal position, and electromagnetic means for causing actuation of said restraining means under different electrical conditions comprising a magnetizable core member, a pole piece for said core member divided into components for dividing the magnetic field, and a plurality of armatures for actuating said restraining means cooperatively related respectively with said pole piece components and spaced at different distances therefrom. 100
23. The combination with a movable contact member, of means for restraining it in normal position, and electromagnetic means for causing actuation of said restraining means under different electrical conditions comprising a magnetizable core member, a pole piece for said core member divided into components for dividing the magnetic field, and a plurality of armatures for actuating said restraining means cooperatively related respectively with said pole piece components and spaced at different distances therefrom. 105
24. Automatic switching apparatus comprising movable contact structure, means for restraining said structure in normal position, electro-magnetic means, and a plurality of armatures, each hinged substantially at an end thereof, and arranged magnetically in parallel in the field of said electro-magnetic means, said armatures selectively attracted upon occurrence of different predetermined circuit conditions to actuate said restraining means substantially at the end of movement of the selected armature. 110
25. Automatic switching apparatus comprising movable contact structure, means for restraining said structure in normal position, an electro-magnetic device, a plurality of armatures arranged magnetically in parallel in the field of said device, each armature pivoted substantially at an end thereof for independent movement by said device mechanically to actuate said restraining means, and means delaying actuation of said restraining means by one of said armatures until an abnormal circuit condition shall have persisted for a substantial period. 115
26. Automatic switching apparatus comprising movable contact structure, means for restraining said structure in normal position, an overload coil, pole structure therefor, a plurality of armatures magnetically in parallel in the field of said coil, each of said armatures pivoted at one end and adapted to engage said pole structure at the other end for actuating said restraining means selectively in response to attainment of predetermined magnitudes of current traversing said coil, and a sucker element operatively connected to one of said armatures. 120
27. Automatic switching apparatus comprising movable contact structure, means for mechanically restraining said structure in normal position, an overload coil, a pair of armatures of substantially different magnetic susceptibility disposed magnetically in parallel in the field of said coil, each of said armatures pivoted at one end and selectively attracted to actuate said restraining means, and means for delaying actuation of said restraining means by the armature of 125

higher magnetic susceptibility until an abnormal circuit condition shall have persisted for a substantial period.

28. Automatic switching apparatus comprising movable contact structure, means for restraining said contact structure in normal position, an overload coil, pole structure therefor, a pair of armatures of substantially different magnetic susceptibility disposed magnetically in parallel in the field of said coil, each armature pivoted substantially at an end thereof, means for delaying actuation of said restraining means by the armature of higher magnetic susceptibility until an abnormal circuit condition shall have persisted for a substantial period, and structure for actuating said restraining means selectively engaged by said armatures as the free end of the selectively moved armature approaches its final position with respect to said pole structure.

29. Automatic switching apparatus comprising movable contact structure, means for restraining said structure in normal position, an overload coil, a pair of armatures of substantially different mass disposed magnetically in parallel in the field of said coil, and having their corresponding ends pivoted co-axially, means for delaying actuation of said restraining means by the armature of greater mass until an overload of magnitude less than the magnitude to which said other armature responds shall have persisted for a substantial period, and structure for separately and selectively actuating said restraining means by said armatures.

30. Automatic switching apparatus comprising movable contact structure, means for retaining said structure in normal position, an electro-magnetic device comprising an overload coil and pole structure, a plurality of armatures disposed magnetically in parallel and unsymmetrically in the field of said coil, each of said armatures pivoted at an end thereof, and tripping means for said retaining means actuated by each of said armatures as its free end approaches its final position with respect to said pole structure in selective response to predetermined overload conditions.

31. An electromagnetic device comprising a coil, a pivoted armature, a time-delay device associated therewith, a second pivoted armature movable instantaneously upon occurrence of predetermined current conditions, and simultaneously adjustable supports for said armature integral with said time-delay device, said supports being located at different distances from the armature pivots to effect change in the relative positions of said armatures upon adjustment of said device.

32. An electric circuit interrupting apparatus comprising, in combination, a first contact-member, a second contact-member, means including a toggle adapted to oppo-

sitely knuckle for swingably actuating the second contact-member into and out of engagement with the first contact-member for respectively closing and opening the circuit, and current flow responsive means including a first swingable armature for knuckling the toggle to open the circuit on short circuit overloads, and a second swingable armature adapted in cooperation with the first armature for knuckling the toggle to open the circuit on simple overloads.

33. An electric circuit interrupting apparatus comprising, in combination, a first contact-member, a second contact-member, toggle means for actuating the second contact-member into and out of engagement with the first contact-member for respectively closing and opening the circuit, and tripping means for the toggle including a pair of cooperating armatures, one armature being calibrated for actuation on short circuit overloads, and the other armature being calibrated to assist the actuation of the first armature on simple overloads.

34. An electric circuit interrupting apparatus comprising, in combination, a first contact-member, a second contact-member, means for actuating the second contact-member into and out of engagement with the first contact-member for respectively closing and opening the circuit, and means for actuating the first means to open the circuit, said last means including a pair of armatures respectively actuatable at maximum and lesser values of current flow and adapted to coact for opening the circuit at less than maximum current flow.

35. Automatic switching apparatus comprising movable contact structure, electro-magnetic means, and a plurality of armatures, each hinged substantially at an end thereof and arranged magnetically in parallel in the field of said electro-magnetic means, said armatures being selectively attracted upon occurrence of different predetermined circuit conditions to actuate said contact structure substantially at the end of movement of the selected armature.

CERTIFICATE OF CORRECTION.

Patent No. 1,914,582.

June 20, 1933.

WILLIAM M. SCOTT.

It is hereby certified that error appears in the printed specification of the above numbered patent requiring correction as follows: Page 6, line 117, for "suckers" read sucker S; and that the said Letters Patent should be read with this correction therein that the same may conform to the record of the case in the Patent Office.

Signed and sealed this 23rd day of January, A. D. 1934.

P. M. Hopkins

(Seal)

Acting Commissioner of Patents.
